UNITED STATES PATENT OFFICE.

CHARLES LE ROY BEALL, OF ALTON, ILLINOIS.

SHOVEL.

1,209,248.

Specification of Letters Patent. Patented Dec. 19, 1916.

Application filed February 17, 1915. Serial No. 8,803.

To all whom it may concern:

Be it known that I, CHARLES LE ROY BEALL, a citizen of the United States of America, a resident of Alton, in the county 5 of Madison, State of Illinois, have invented certain new and useful Improvements in Shovels, of which the following is a full, clear, and exact description, reference being had to the accompanying drawings, forming 10 a part of this specification.

My invention relates to improvements in shovels, and more specifically stated, to means for reinforcing shovel blades at the junctions of the handle sockets and the rear 15 walls of the shovels, and also at the junctions of the rear walls and bottoms of the blades.

The main object of the invention is to produce a strong shovel that is very materially reinforced at points which are subjected to 20 severe strains and the improvement lies in a specific arrangement of ribs, pressed from the shovel blade in a particular manner to most effectively reinforce said points.

Prior to this invention, shovel blades have 25 been reinforced by ribs located adjacent to the handle sockets, and also by ribs extending from points near the handle sockets to points near the transverse centers of the shovel blades. Shovels are subjected to severe 30 strains at these points, and many attempts have been made to produce reinforcing elements capable of preventing breakage at such points without materially reducing the capacity of the shovels, and without deflecting the material thrown from the shovels. However, in so far as I am aware, the prior reinforcing elements have not been entirely successful.

Therefore, an important object of my invention is to produce a precise arrangement of ribs of a particular shape, pressed from the shovel blade, and located in certain relative positions with respect to each other and with respect to the handle socket; so as to serve 45 as reinforcing elements which provide the required strength at the points which have not heretofore been amply reinforced.

Figure I is a top or plan view of my shovel, a portion of the handle being broken 50 away. Fig. II is a vertical section taken on the longitudinal center line of the shovel. Fig. III is a transverse section taken on the line III-III, Fig. II. Fig. IV is a section taken on the line IV-IV, Fig. II. Fig. V 55 is a section taken on the line V-V, Fig. I.

The shovel blade and handle socket are

made from a single piece of sheet metal, pressed to form a bottom 1, side walls 2, a rear wall 3, a tubular handle socket 4, reinforcing ribs 5 and a reinforcing web 6. A 60 handle 7 is fitted to the handle socket 4.

A tubular handle socket 4 merges into and terminates at rear wall 3, and the reinforcing ribs 5 merge into said handle socket and diverge from each other at said rear wall. 65

The reinforcing ribs 5 are separated from each other at the junction of the rear wall and bottom wall, and the metal is pressed outwardly at the junction of said walls to form the sloping web 6 which lies between 70

and merges into the diverging portions of said ribs 5. While the crowns of the ribs 5 gradually merge into each other, at the same time merging into the tubular handle socket, it will be noted that said ribs are approxi- 75

mately straight and approximately parallel with each other at points on opposite sides of the transverse center of the bottom wall 1. The object in forming the ribs and web in this precise manner is to very greatly reinforce 80 the structure at the points where it is subjected to the most severe strains in service, at the same time arranging the web and ribs in such a manner that they will not deflect or retard the material thrown from 85 the shovel.

The ribs 5 merging into the handle socket, distribute the strains to points on opposite sides of the longitudinal center of the shovel, and these ribs are well adapted to resist the strains tending to break the blade at the inner end of the handle socket. It is important to note that the ribs 5 are separated from each other at the junction of the bottom 1 and rear wall 3, for the tendency 90 to bend and break at this point is very great, and the separated ribs merging into web 6 and handle socket 4 are capable of resisting the most severe strains at said point. I deem this specific structure an important improvement because in so far as I am aware, shovels have never been amply or perfectly reinforced at the points referred to. 95

I claim:—

1. A sheet metal shovel blade pressed to form a bottom, a rear wall, a handle socket merging into said rear wall, and a pair of ribs having crowns which merge into each other and into said handle socket at said rear wall, said ribs being so formed that they diverge from each other at said rear 100 110

wall and extend along said bottom, and a sloping web being formed between the diverging portions of said ribs.

2. A sheet metal shovel blade pressed to
5 form a bottom, a rear wall, a handle socket
terminating at said rear wall, and reinforcing ribs merging into said handle socket and
diverging from each other at said rear wall,
said reinforcing ribs being separated from
10 each other at the junction of said rear wall

and bottom, and the metal being pressed
outwardly at the junction of said rear wall
and bottom to form a sloping web which lies
between and merges into the diverging por-
tions of said ribs.

CHARLES LE ROY BEALL.

In the presence of—

E. H. BEALL,
L. G. HEINTZ.
